UNITED STATES PATENT OFFICE.

GUY G. CRANE, OF ROCKFORD, ILLINOIS.

CAR-OILER.

No. 921,594.

Specification of Letters Patent. Patented May 11, 1909.

Application filed June 22, 1908. Serial No. 439,800.

To all whom it may concern:

Be it known that I, GUY G. CRANE, a citizen of the United States, residing at the city of Rockford, in the county of Winnebago and State of Illinois, have invented certain new and useful Improvements in Car-Oilers; and I do declare the following to be a full, clear, and exact description of the invention, such as will enable others skilled in the art to 0 which it appertains to make and use the same.

This invention relates to an improved oiling device especially adapted for use as a car oiler.

5 The object of the invention is to provide an oiler having a pump constructed to deliver the required amount of oil and no more to the desired place.

Another object of the invention is to provide 0 a device of this character which is simple in construction and efficient in operation and the parts of which may be readily taken apart for cleaning and other purposes.

With these and other objects in view, the 5 invention consists of certain novel features of construction, combination and arrangement of parts, as will be more fully described and particularly pointed out in the appended claim.

10 In the accompanying drawings, Figure 1 represents a vertical section of an oiler constructed in accordance with this invention; Fig. 2 is a detail vertical section on the line 2—2 of Fig. 1.

15 In the embodiment illustrated an oil containing receptacle 1, is shown of any desired shape and size and which is preferably composed of sheet metal. This vessel 1 is provided with a bottom 2, preferably made as shown 20 with a flange 3, depending from its lower face around its outer edge and secured to the sides of the vessel 1 in any suitable manner, it being designed to space the bottom a suitable distance from the lower edge of the 25 receptacle.

A pump is mounted within the receptacle 1, and preferably comprises a supporting base 4, secured to the bottom 2, by bolts, as 5, or in any other suitable manner. This 50 base member 4, is provided with an oil chamber 6, having an inlet 7, provided with a strainer 8, whereby the oil passing therethrough to the pump is strained to prevent dirt or any other object from entering 55 through the inlet and clogging the pump.

A valve 9 is arranged in said inlet 7, and is preferably made in the form of a ball disposed within the chamber 6, and adapted to normally close said inlet. A screw cap 10, is arranged above the valve 9, to permit access thereto for cleaning or other purposes, and it is also designed to prevent said ball from becoming displaced. The oil chamber 6, is also provided preferably at a point opposite the inlet 7 with an outlet 11 normally closed by an outwardly opening valve 12 which is also preferably made in the form of a ball with a cap 13 screwed into an opening arranged thereover similar to the cap 10 of the inlet valve. A pipe 14 is connected with 70 the outlet 11 in any suitable manner and extends upwardly through the top of said receptacle 1 and its outer end is connected with a hose 15 which may be of any suitable size or length and is designed to convey the oil to 75 any point to which it is desired to apply it, thereby avoiding the necessity of moving the receptacle 1 from place to place. An outwardly opening spring pressed valve 16 is arranged to close the outer end of the hole 15. 80 to prevent oil from dripping therefrom when the device is not in use.

A pump cylinder 17 composed of brass or any other suitable material is connected at 85 its lower end with the base 4 above the oil chamber 6, and a piston 18 of any suitable material preferably composed of hard wood is mounted to slide within said cylinder. A piston rod 19 is connected at one end with said piston 18 and extends upwardly through a sleeve 21 connected with the top 22 of the receptacle 1. This piston rod 19 is provided at its outer end with a handle 20 for operating the piston or plunger and for lifting the vessel 1 when it is desired to move it from 95 place to place. At its inner end it has an enlarged portion 19^a in which is an annular groove 19^b. A suitable packing 23 is arranged in said sleeve around the piston rod 19 to form an oil-tight connection therewith.

A collar 24 is adjustably mounted on the piston rod 19 by means of a set screw 25 and is adapted to be fastened at any desired point on said rod 19 for regulating the stroke of the piston and the amount of oil to be delivered. A spring 26 is slidably mounted on the underneath side of the top 22 by bolts 28 which extend through a slot 27 formed in the cover 22 and the free end of the spring is arranged to engage the piston groove 19^b when 110

the spring is pushed inward to hold the pump piston in lifted position when the oiler is not in use.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention, as defined in the appended claim.

15 I claim as my invention:

In a device of the class described the combination with a containing vessel, a removable top therefor, a pump cylinder mounted

in the vessel and having valved inlet and outlet ports, a piston operating in said cylinder, a piston rod connected to said piston and having an annular groove adjacent thereto, a collar adjustably surrounding said rod to determine the amount of fluid injected by said pump, and a slidably mounted spring catch carried on the inside of said top and adapted to engage the groove to hold the piston in elevated position.

20 In testimony whereof I have hereunto set my hand in presence of two subscribing witnesses.

30 GUY G. CRANE.
